UNITED STATES PATENT OFFICE.

MARK B. CLAFF, OF RANDOLPH, MASSACHUSETTS; C. LLOYD CLAFF ADMINISTRATOR
OF MARK B. CLAFF, DECEASED.

BOX COVER AND METHOD OF MAKING THE SAME.

Application filed February 24, 1926. Serial No. 90,501.

This invention relates to a cover for paper boxes and the like and to a method of making the same.

One object of the invention is to provide a box cover of the character specified of novel and improved construction which is strong, durable, and which may be manufactured at minimum expense.

A further object of the invention is to provide a cover for paper boxes and the like, and particularly boxes of the character of shoe boxes in which the outer surface of the cover is finished by a finishing sheet adhesively applied to and covering the outer surface of the cover, which is strong, durable, and which lends itself particularly to economical production by automatic machinery.

Further objects of the invention are to provide a novel and economical method for the production of the improved cover.

These and other features of the invention will be hereinafter described and particularly defined in the claims at the end of this specification.

The drawings illustrate the invention as embodied in a cover for a shoe box, and also illustrate several steps in the method of producing the same, and wherein Figure 1 is a perspective illustrating the application of the finishing sheet to a strip of the fibrous material from which the body portion of the cover is formed; Fig. 2 is a cross-section taken on the line 2-2 of Fig. 1; Fig. 3 is a perspective of one of the blanks formed from the strip shown in Fig. 1; Figs. 4 and 5 are cross-sectional views illustrating the formation of the end pieces employed in the construction of the box cover; Fig. 6 is a perspective of a portion of the box cover in the stage of its completion, wherein one of the end pieces is affixed to the end flap and to the sides; Fig. 7 is a vertical section through the end of the box cover illustrated in Fig. 6; Fig. 8 is a perspective of one end of the completed box cover; Fig. 9 is a vertical section through one end of the completed box cover; and Fig. 10 is a cross-section on line 10-10 of Fig. 3.

The present invention is particularly adapted to be embodied in covers for paper boxes, such as shoe boxes and the like, wherein the cover is provided with a finishing sheet of paper for finishing the outer surface thereof. In practice these boxes and covers

are made of cardboard, pasteboard, or similar material, usually of a darker color, such as gray, and it is desirable that a white or other colored finishing sheet of paper or similar material be affixed to the outer surfaces of both the cover and the box to enhance the appearance thereof and to impart to the box or cover certain additional strength. At the present time most of the box covers are covered with the finishing sheet by hand, and it is one of the aims of the present invention to provide a construction of box cover which may be produced from blanks of the cardboard or other material, to which the covering or finishing sheet is affixed prior to the formation of the cover, and preferably while the blank is in a substantially flat form. By affixing the covering sheet in this manner, relatively simple mechanism may be employed in affixing the finishing sheet to the blanks, enabling rapid and economical production to be attained.

Referring to the drawing, 10 represents a sheet of cardboard, pasteboard or the like, from which the body portion and sides of the present cover are formed, and in accordance with the preferred method of manufacturing the present box cover, a finishing sheet 12 of paper or other finishing material, is adhesively affixed to one surface of the sheet 10. The finishing sheet 12 is preferably of slightly greater width than the cardboard sheet 10 and the side portions 14 thereof are folded over and adhesively affixed to the opposite surface thereof, forming finished side edges 15. In practice these operations may, if desired, be performed by relatively simple machines of standard construction, and conveniently both the cardboard or like sheet 10 for forming the body portion and the sides of the cover, and the finishing sheet 12 may be drawn as webs from supply rolls 16, 17, as illustrated in Fig. 1, and the finishing sheet may be applied in the manner above described, producing a covered web from which the individual blanks may be cut.

After the finishing sheet 12 has thus been applied to the sheet 10, individual cover blanks 20 are cut therefrom. Each cover blank 20 for forming the body portion and sides of the cover is preferably shaped, as illustrated in Fig. 2, having side portions

21, 22, each provided at their ends with triangular-shaped tabs 24 which, in the finished product, are adapted to be folded around the corners of the cover and to constitute a portion of the end walls thereof. The cover blank 20 is also provided with an end flap 25 at each end thereof, and the end flaps 25 are preferably made of a width equal to the depth of the box cover, and each flap 25 is formed of a shape such that when folded into a position at substantially right angles to the top of the cover, the edges 27 thereof cooperate with the edges 28 of the triangular tabs 24 to form an end wall of the cover.

2 Provision is made for connecting the tabs 24 and end flap 25 at each end of the box cover to form the completed ends of the cover, and for this purpose, in accordance with the preferred method, an end piece 30 is secured to the outer side of the end tabs 24 and end flap 25 in the manner illustrated in Fig. 6. Thereafter the upper portion 31 of the end piece 30 is folded over and affixed to the inner faces of the end flap 25 and the tabs 24 producing a construction of end wall, illustrated in section in Fig. 9.

3 In order that the outer surface of the end pieces 30 may be provided with a finishing sheet, I prefer to adhesively affix a finishing sheet 40 to one surface of each end piece 30, prior to the incorporation of the end piece with the cover. The finishing sheet 40 may and preferably will be applied to each end piece 30 while the latter is in a substantially flat condition, such as is illustrated in Fig. 4. In order to minimize wastage of the material comprising the finishing sheet 40, I prefer to utilize a sheet 40 of such width that when applied to the outer surface of the end piece, one edge portion 41 projects beyond that edge 42 of the end piece which is to comprise the lower edge of the outer portion of the end piece in the finished box, and so that the second edge portion 43 of the finishing sheet will extend down sufficiently upon the inner faces of the completed end walls of the box cover to match the side portions 14 thereof, and to thereby impart to the interior of the finished box cover a neat and trim appearance in this respect. An end piece having a finishing sheet applied in this manner is illustrated in cross-section in Fig. 4, and the next step in the operation consists in folding over the projecting edge 41 and affixing it to the opposite surface of the end piece, producing an end piece of the construction illustrated in Fig. 5. An end piece thus finished is then adhesively affixed to the outer surface of each end flap 25 and its cooperating tabs 24, as illustrated in Fig. 7, and thereafter the upper portion 31 of each end piece is folded over the end flap 25 and tabs 24 and is preferably adhesively affixed to the

inner surfaces thereof, producing a relatively rigid construction of end wall of the cover.

4 In order to further strengthen the corner portions and side edges of the box, I prefer to utilize stay strips 48 along the side edges of the box cover, and which are represented in Fig. 10 as comprising paper strips folded over the side edges and adhesively affixed to the opposite surfaces of the sides of the box cover. In the completed cover the stay strips 48 are concealed from view by the finishing sheet 12 and the side portions 14 thereof. The stay strips extend to the tabs 24 so that when the box cover is produced the stay strips extend around the corners of the box cover and serve to reinforce the same. The stay strips, together with the finishing sheet 12, comprise double portions connecting the tabs 24 with the sides of the box cover, and being folded around the corners they operate to produce a very strong construction of corner.

5 The present construction of cover may be economically manufactured, not only because the operations involved in the manufacture thereof are simple, but also because of the fact that wastage of stock is reduced to a minimum. When the invention is embodied in box covers in which the outer surface, body portion, sides and ends are covered with a finishing sheet, then considerable economy in the manufacture of the box over the ordinary hand wrapping methods may be accomplished because of the fact that both body portion and sides and also end pieces may be formed from strips of material which have been covered while in flat form. In this manner simple forms of sheet applying and folding mechanism may be employed to cover these strips with the finishing sheet, and then the body blanks and end pieces may be economically and rapidly die cut, and thereafter the box cover assembled in a simple and economical manner, doing away entirely with the hand operation heretofore employed in applying the finishing sheets to the cover.

6 Having thus described the invention, what is claimed is:—

7 1. A cover for paper boxes and the like comprising a body portion provided with sides folded at substantially right angles thereto, triangular shaped end tabs integral with said sides and folded around each corner of the cover to constitute a part of the end wall, end flaps of a width substantially equal to the depth of the cover, formed at each end of the body portion and provided with cut away portions which cooperate with said end tabs to permit the end tabs and end flaps to be aligned, said end flaps being folded at right angles to the body portion so that the upper edges thereof lie substantially in the plane of the upper edges

of the sides of the box, and separate end pieces for each end of the cover secured to the outer surfaces of the end flaps and end tabs and folded thereover and affixed to the inner surfaces thereof.

2. A cover for paper boxes and the like comprising a body portion having sides folded at substantially right angles thereto, and a flat portion between the sides constituting the top of the cover, an end flap extending from the end of each side portion, an end-flap extending from each end of the top forming portion, all of said flaps being folded to form the ends of the box and being

of a width such that the upper edges thereof lie substantially in the plane of the upper edges of the sides of the box, and separate end members having finishing material covering the outer surface thereof adhesively affixed to the outer surfaces of each set of the flaps thus folded and having a portion folded over and into the interior of the box and being adhesively affixed to the inner surfaces of said flaps.

In testimony whereof I have signed my name to this specification.

MARK B. CLAFF.
